FIRE EXTINGUISHER

Hugo Leipold, Buffalo, N. Y., assignor to Buffalo Fire Appliance Corporation, Buffalo, N. Y., a corporation of New York

Application June 1, 1936, Serial No. 82,803

2 Claims. (CL 299—97)

This invention relates to a fire extinguisher and more particularly to a fire extinguisher of the portable type comprising a liquid receptacle within which is arranged a double acting pump actuated by a plunger and handle to forcibly eject the liquid from the receptacle on both the inward and outward movements of the plunger and regardless of the position in which the extinguisher may be held.

10 One of the principal difficulties in extinguishers of this type is to provide such an extinguisher which, when not in operation, is sealed both against the escape of the fire extinguishing liquid and also sealed against the entrance of air but which will, when operated, permit air to enter the receptacle and replace the fire extinguishing liquid as it is discharged. To permit this, the principal object of the invention is to provide, as a seal for the plunger, a series of thin disk-like metal washers alternating with fiber washers, the metal washers when the plunger is in repose providing a liquid and air-tight seal and, when flexed by the movement of the plunger, permitting air to pass and displace the liquid being discharged.

20 Another purpose of the present invention is to provide a simple and inexpensive means for insuring a discharge of the liquid regardless of the position in which the extinguisher may be held and in particular to provide a simple and inexpensive construction of the check valves used in conjunction with the double acting pump.

30 A further object of the present invention is to insure free rotation of the pump casing within the receptacle and in particular to employ a felt washer between the pump and the casing so as to prevent corrosion at this point and consequent interference with the free rotation of the pump.

35 Another object of the present invention is to provide adequate means for stripping all of the liquid from the pump plunger as it is withdrawn.

In the accompanying drawing:

Fig. 1 is a longitudinal central section, through a fire extinguisher embodying my invention.

45 Figs. 2 and 3 are transverse sections, taken on the correspondingly numbered lines of Fig. 1.

Fig. 4 is a fragmentary view similar to Fig. 1 on an enlarged scale.

The fire extinguisher is shown as having a cylindrical casing 5 having an end head 6 through which the fire extinguisher liquid is discharged and having an end head 7 through which the pump is operated. A discharge nozzle 8 extends through and is secured to the head 6 and is provided with a discharge orifice 9. This nozzle 8

supports a discharge tube 10 which is rigidly secured to the nozzle 8 and projects through an opening 11 provided in the opposite end head 7. The pump includes a cylinder 12 and a plunger 13 which is disposed inside of the cylinder 12 and surrounds the discharge tube 10. One end of the cylinder 12 is enclosed by an end head 14 which is preferably die cast and is rigidly secured to the cylinder 12. This end head 14 is formed to provide a bearing 15 which engages the discharge tube 10 near the discharge end thereof. In order to prevent leakage past the bearing 15 the outer end of the end head 14 is recessed and a felt washer 16 is placed in this recess and held therein by a metal washer 17 which can be secured to the end head 14 in any suitable manner. In order to prevent corrosion from affecting the free rotation of the pump cylinder and end head 14 a felt washer 18 is arranged around the discharge tube 10 and between the discharge nozzle 20 8 and the washer 17. The opposite end of the pump cylinder 12 is enclosed by an end head 20 which is also preferably made in the form of a die casting and is formed to provide a bearing 21 which is supported by the pump plunger 13. 25 This head 20 is rigidly secured to the cylinder. Leakage is prevented through the bearing 21 by a felt washer 22 and this felt washer is retained in place by a bronze washer 23 which also serves to provide additional bearing surface for the head 30 20 in its movement around the plunger 13.

The plunger 13 operates a piston 25 which has a limited sliding movement on the plunger 13. This piston 25 can be of any suitable form but is preferably provided with felt packing rings 35 26 to prevent the escape of liquid past the piston. The limited sliding movement of the piston 25 is provided by a stop ring 27 rigidly secured around the plunger 13 and an end nut 28 which is screwed on the inner end of the plunger and 40 also serves to enclose the end of the plunger. This nut 28 provides a bearing 29 around the discharge tube 10 which prevents the escape of extinguisher liquid from inside of the plunger into the end of the pump cylinder near the discharge 45 end of the extinguisher. As the plunger is reciprocated the piston 25 is moved back and forth between the ring 27 and the nut 28. In one extreme position it covers a series of ports 30, as illustrated in Fig. 1, and in the other extreme 50 position it covers the series of ports 32.

In order to provide for the necessary check valves and also to withdraw the fire extinguisher liquid from the bottom of the receptacle 5 regardless of what position the container may as- 55

sume each end head 14 and 20 is extended laterally in the same direction as indicated at 33 and 34. These extensions form weights which serve to rotate the entire pump cylinder as the container 5 is rotated. The lateral extension 33 is formed to provide a ball cage 35 for an inwardly opening check ball 36 which seats on a seat surrounding an orifice 37. The ball 36 is retained in the cage 35 by the pump cylinder 12 and in order to permit the extinguisher liquid passing the check ball 36 to enter the corresponding end of the cylinder 12 a slot 38 is provided in the side of the cylinder registering with the cage 35. This slot 38 is, of course, smaller than the check ball 36 so that the ball 36 cannot enter the pump cylinder. The lateral extension 34 of the opposite end head 20 is likewise formed to provide a ball cage 40 which houses a check ball 41 seating around an orifice 42 in the lateral extension. The pump cylinder 12 is provided with a slot 43 registering with the cage 40, which slot permits the liquid to be drawn past the check ball 41 into the corresponding end of the pump cylinder 12 but retains the ball 41 in the cage 40. The two lateral extensions 33 and 34 are connected by a tube 45 which is preferably arranged parallel with the major axis of the fire extinguisher and communicates at one end with a passage 46 in the lateral extension 33 and at its other end with a passage 47 in the lateral extension 34. The passage 46 communicates with the orifice 37 and at its outer end is formed to provide a seat 48 against which a ball 49 is adapted to seat. This ball 49 is contained within a chamber 50 which is enclosed by a disk 51. An orifice 52 at the extreme lower corner of the extension 33 nearest to the head 6 establishes communication between the chamber 50 and the interior of the receptacle 5.

The passage 47 of the lateral extension 34 communicates with the orifice 42 and is also formed to provide a seat 55 against which a ball 56 seats. This ball is contained within a chamber 57 which is enclosed by a disk 58 similar to the disk 49. Communication between the chamber 57 and the interior of the receptacle is established by a small port 59 at the lower corner of the extension 34 nearest to the end head 7 of the receptacle. The two balls 49 and 56 are connected by a rod 60 so that when one is seated on its seat the other is positively unseated.

A gland which also forms the air admitting means is provided between the plunger 13 and the end head 7. This gland includes a collar 61 extending centrally through the end head 7 and soldered or sweated to this end head is a locking ring 62 which is secured to the outer face of the end head 7, teats 63 being provided in the end head 7 and engaging recesses in the locking ring 62 to assist in preventing rotation of the locking ring 62. The collar 61 is recessed and in this recess are provided three fiber washers 64 alternating with thin, disk-like bronze washers 65. The bronze washers 65 have a working clearance (.003 of an inch) around the plunger 13 and are bodily displaced and also distorted, together with the intercalated fiber washers when the plunger is moved in either direction. A washer 66 between the end head 20 of the pump cylinder and the collar 61 serves to retain the fiber and bronze washers 64, 65 in operative position in the recess in the nut 61.

To the end of the plunger 13 is screwed a nut 68 which extends beyond the end of the plunger and is formed to provide a space 69 which permits the fire extinguishing liquid to escape from

the interior of the plunger 13 into the interior chamber 70 of a handle 71. This handle 71 has a screw connection with the nut 68, the nut 68 being provided with screw driver slots 72 in order to screw it into the handle 71. The escape of liquid from the chamber 70 is prevented by a pair of cork washers 73 and also by a washer 74 which, when the handle is locked in position, has a sealing engagement with the collar 61. In order to prevent the cork washer 73 from being ground against the screw driver slot 72 as the handle is turned, a protecting washer 75 is provided. The locking means for the handle consists of a pair of ears or lugs 76 extending outwardly from the base of the handle 71 and adapted to engage under segmental locking shoulders 78 provided on opposite sides of the locking ring 62. It will be understood that the underside of these shoulders 78 are inclined so that when the ears 76 are caught under these shoulders and the handle is turned a quarter turn or less the washer 74 and cork washers 73 are compressed to provide a tight seal.

As an additional seal against the escape of liquid from the fire extinguisher the end of the liquid discharge tube 10 is sealed when the handle is locked. To this end a small cup-shaped cap 80 is arranged in the chamber 70 of the handle and is provided with an open end in which the end of the discharge tube 10 enters. The sealing cap 80 contains a plurality of sealing disks 81, that engaging the end of the tube 10 being preferably made of rubber, or the like, and being backed by fiber disks. A compression spring 82 is arranged in back of the sealing cap 80 in order to firmly and yieldingly press the cap against the end of the discharge tube.

With the extinguisher constructed as above described and filled with liquid through a filling opening closed by a plug 83 the operation of the extinguisher is as follows, it being assumed that it is desired to discharge a stream of fire extinguishing liquid downwardly.

The operator first turns the handle a quarter turn so as to release the locking ears 76 from under the quadrantal shoulders 78 of the locking ring 62. This permits him to draw the handle 71 outwardly and since this handle is connected through the nut 68 with the plunger 13 this movement draws the plunger 13 outwardly. The pressure of the liquid in the end of the cylinder 12 causes the piston 30 to move against the end cap or nut 29. This closes the ports 32 and opens the ports 30. At the same time the outward movement of the handle 71 releases the sealing cap 80 from engagement with the end of the discharge tube 10. Consequently, the fire extinguishing liquid contained in that end of the pump cylinder 12 nearest to the head 7 will be forced through the ports 30; through the space between the plunger 13 and the discharge tube; and through the space between the nut 68 and the discharge tube into the chamber 70 in the handle from which it is discharged through the open end of the discharge tube 10 and out through the discharge nozzle 8.

As the plunger is moved outwardly the piston 25 draws the fire extinguishing liquid from the receptacle 5 through the port 52 into the chamber 50 and past the ball 49 into the passage 46, this ball 49 being unseated when the fire extinguisher is tilted downwardly, as assumed, and the fire extinguishing liquid from the passage 46 is drawn past the check ball 36 and slot 38 into the end of the cylinder nearest to the end head 75

6. This end of the cylinder 12 is therefore filled while the opposite end is being discharged.

When the operator reaches the end of the outward stroke he moves the handle inwardly. This 5 immediately causes the piston 25 to move against the collar 27, thereby closing the ports 30 and opening the ports 32, and also causes the ball check 36 to seat. Therefore the fire extinguishing liquid in the end of the pump cylinder 12 10 nearest to the end head 6 is forced through the ports 32 up the plunger 13, past the nut 68 into the chamber 70 in the handle 71, from which it is discharged through the discharge tube 10 and nozzle 8. At the same time fire extinguishing 15 liquid is drawn into the opposite end of the pump cylinder 12 through the port 52, chamber 50, past the unseated ball 49, passage 46, tube 45, passage 41, orifice 42, past the check ball 41 and through the slot 43.

20 Since the entire pump cylinder 12 and its end heads 14 and 20 are free to rotate around the discharge tube 10 and plunger 13, the lateral extensions 33 and 34 always assume the dependent position shown in Fig. 1. Therefore the extinguishing liquid is drawn from the lowermost part 25 of the receptacle 5 because the balls 49 connected by the bar 60 insure that the fire extinguishing liquid is only withdrawn through the port 52 or 30 59 of that end head which is lowermost. Therefore in the downwardly tilted position of the fire extinguisher assumed substantially the entire contents of the extinguisher will be withdrawn through the port 52 and discharged.

If it is desired to discharge the contents of the 35 fire extinguisher upwardly the tilting of the extinguisher causes the ball 49 to seat and the ball 56 to unseat and therefore the liquid from the receptacle will be entirely discharged through the port 59.

40 It will be appreciated that the free rotation of the pump cylinder is essential and to this end the fiber washer 18 is employed to prevent any corrosive sticking between the washer 17 and the discharge nozzle 8. It will also be noted that the 45 cage for the check balls 36 and 41 is provided in part by the pump cylinder 12 by the simple expedient of providing the slots 38 and 43 in the cylinder. This avoids the unnecessary expense of specially forming the entire check valve assembly in the end heads.

50 As the liquid is discharged from the receptacle 5 it is necessary to replace the discharge liquid with air since otherwise a partial vacuum would be created which would prevent the complete discharge of the contents. Applicant effects the 55 admission of air through the gland in the end head 7 by means of the thin metal washers 65 interposed between the fiber washers 64. As the piston rod 13 is moved in either direction it bodily displaces the metal washers 65 and also 60 flexes these washers and distorts the packing as a whole. The bodily movement of the metal and

fiber washers permits air to pass between the washers and the piston rod and also between these washers and the socket in which they are located, breaking any liquid seal and thereby providing a breather for the extinguisher. 5 Without the metal washers floatingly supported between the fiber washers the felt would compress and become set or permanently packed at the end of the socket. By the provision of laminations of flexible metal and fiber washers this 10 permanent compression or setting of the felt packing is avoided and the packing maintained at full efficiency as a breather and seal.

15 From the foregoing it is apparent that the present invention provides a very simple and inexpensive hand operated fire extinguisher of the double acting pump type in which the mechanism is simplified and the cost reduced as compared with other fire extinguishers of this type and in which the fire extinguisher will continue 20 to function properly without danger of the parts corroding and sticking. It will further be seen that applicant's means for permitting the entrance of air to replace the liquid discharged from the receptacle provides an air and liquid-tight seal when the fire extinguisher is not being used and also provides a means for stripping any fire extinguishing liquid remaining on the 25 plunger 13 before it is withdrawn from the receptacle. 30

I claim as my invention:

1. A packing and breather for a plunger pump mounted in an enclosed container and discharging the liquid therefrom, comprising a member mounted on said container and surrounding said plunger, said member being formed to provide a cylindrical socket around said plunger, a plurality of fibrous washers in said socket and around said plunger and a plurality of metal washers intercalated with said fibrous washers and free 40 to be bodily displaced under the influence of the piston rod thereby to permit the passage of air through the packing while said piston rod is being moved and preventing a permanent compression of the packing. 45

2. A packing and breather for a plunger pump mounted in an enclosed container and discharging the liquid therefrom, comprising a member mounted on said container and surrounding said plunger, said member being formed to provide a 50 cylindrical socket around said plunger, a plurality of flat disk-like fibrous washers in said socket and around said plunger and a plurality of flat, flexible metal washers intercalated with said fibrous washers and free to be bodily displaced and flexed under the influence of the piston rod thereby to permit the passage of air 55 through the packing while said piston rod is being moved and preventing a permanent compression of the packing. 60

HUGO LEIPOLD.
